UNITED STATES PATENT OFFICE.

JOHN W. PAUL, OF KITTANNING, PENNSYLVANIA.

TYPE-WRITER.

No. 901,998.

Specification of Letters Patent.

Patented Oct. 27, 1908.

Application filed July 5, 1906, Serial No. 324,905.

To all whom it may concern:

Be it known that I, JOHN W. PAUL, a citizen of the United States, residing at Kittanning, in the county of Armstrong and State 5 of Pennsylvania, have invented new and useful Improvements in Type-writers, of which the following is a specification.

This invention relates to typewriters and consists in certain improvements in the construction thereof as will be hereinafter fully 10 described and pointed out in the claims.

The invention is illustrated in the accompanying drawings as follows:—Figure 1 shows a side elevation of the typewriter 15 with my device in place therein. Fig. 2, a side elevation of the auxiliary frame of the typewriter. Fig. 3, a plan view of said auxiliary frame, the same being partly in section to better show construction. Fig. 4, an end 20 elevation of said auxiliary frame, a part of it being in section to better show construction.

A marks the main frame of the machine. This may be of any desired form but preferably of such form as to adapt it for a front 25 strike typewriter. Extending inwardly from the main frame are the supporting lugs *a*. These lugs are each provided with an annular groove *a'*. An auxiliary frame *B* has the plates *b* at the sides, the plate *b'* at the rear 30 end, and the cross plate *b*² at the front. The rear end of the plate *b* is notched at *c'*, the notch being of such proportion as to fit in the groove *a'*. Near the front ends of the 35 side plates and extending upwardly from the bottom thereof are the notches *c*². The front sides of the notches have the bevel *c*³, the sides of the notches *c*² being such as to fit in the groove *a'*.

The basket *C* of the typewriter is mounted 40 in the auxiliary frame *B*. It is preferably pivotally mounted, the arms *C'* carrying the basket being pivoted at *c* on the sides of the frame. By pivotally mounting the basket upper and lower case letters may be obtained 45 in the well known manner. The key levers *D* are also mounted in this auxiliary frame and are so positioned as to come into proper relation to the universal bar *E* when the auxiliary frame is in place in the main 50 frame as clearly shown in Fig. 2. By this construction the type bars and incidental mechanism (not shown) may be easily removed from the machine to give access to the part and for the convenience of assembling. When the auxiliary frame is placed in

the main frame it is rigidly mounted, that is it is not rocked or moved in the operation of the machine, the type basket being moved relatively to the auxiliary frame.

What I claim as new is:—

1. In a typewriter, the combination of a main frame; a universal bar mounted on the main frame; an auxiliary frame removably mounted in the main frame; and the type basket and key levers mounted in the auxiliary frame, said key levers being in position to actuate the universal bar when the auxiliary frame is mounted in the main frame and the type basket being movably mounted in the auxiliary frame. 60

2. In a typewriter, the combination of a main frame; a universal bar mounted in said main frame; an auxiliary frame removably and fixedly mounted on the main frame; a type basket mounted in the auxiliary frame; 65 said basket being movable in the auxiliary frame for upper and lower case letters and key levers mounted in the auxiliary frame, said key levers being in position to actuate the universal bar when the auxiliary frame 70 is in place. 75

3. In a typewriter, the combination of a main frame having the lug *a* extending from the sides thereof, said lugs being provided with the groove *a'*; an auxiliary frame having the side plate *b* in which are arranged the slots *c'* and *c*² in proper relation to permit the mounting of said auxiliary frame with the sides of the slots in said plates around the lugs *a* and in the grooves *a'*. 80 85

4. In a typewriter, the combination of a main frame having the lug *a* extending from the sides thereof, said lugs being provided with the groove *a'*; an auxiliary frame having the side plates *b* in which are arranged the slots *c'* and *c*² in proper relation to permit the mounting of said auxiliary frame with the sides of the slots in said side plates around the lugs *a* and in the grooves *a'*; the type basket *C* pivotally mounted between the side 90 95 plates *b* and the key levers *D* carried by said auxiliary frame. 100

5. In a typewriter, the combination with a main frame and platen; of a universal bar mounted in the main frame; an auxiliary frame removably mounted in the main frame; and a type basket and key levers mounted in the auxiliary frame, the basket being movable in the auxiliary frame for upper and lower case letters and adapted to 105 110

carry type bars arranged to strike the front of the platen, and the key levers being adapted to actuate the universal bar.

6. In a typewriter, the combination with a main frame and platen; of an auxiliary frame removably mounted in the main frame; a type basket mounted in the auxiliary frame, adapted to carry type bars arranged to strike the front of the platen; said basket being movable in the auxiliary frame for upper and lower case letters and means for changing the relations of the type basket and platen for upper and lower case letters.

7. In a typewriter, the combination with a

main frame and platen; of an auxiliary 15 frame removably mounted in the main frame; and a type basket mounted in the auxiliary frame, and movable therein relatively to the platen for upper and lower case letters, and adapted to carry type bars 20 arranged to strike the front of the platen.

In testimony whereof I have hereunto set my hand in the presence of two subscribing witnesses.

JOHN W. PAUL.
